[57] CLAIM

The ornamental design for case for video tape cassette, as shown and described.

DESCRIPTION

FIG. 1 is a top plan view of a case for video tape cassette showing my new design;

FIG. 2 is a front elevational view thereof;

FIG. 3 is a left side elevational view thereof;

FIG. 4 is a right side elevational view thereof;

FIG. 5 is a cross-sectional view thereof as taken from line A—A of FIG. 2;

FIG. 6 is a top plan view of FIG. 7;

FIG. 7 is an extended plan view thereof showing the case in the open position;

FIG. 8 is a left side elevational view of FIG. 7;

FIG. 9 is a right side elevational view of FIG. 7;

FIG. 10 is a bottom and left rear perspective view thereof.
